STAPLING MACHINE OR THE LIKE

Rudolf Tauber, Brooklyn, N. Y.

Application October 29, 1953, Serial No. 27,373

Term of patent 14 years

(Cl. D74—1)

To all whom it may concern:

Be it known that I, Rudolph Tauber, a citizen of the United States of America, residing in Brooklyn, in the county of Kings and State of New York, have invented a new, original, and ornamental Design for a Stapling Machine or the like, of which the following is a specification, reference being had to the accompanying drawing, forming a part hereof.

The figure on the drawing is a side perspective view of a stapling machine, showing my new design; the opposite side being substantially the same in appearance.

I claim:

The ornamental design for a stapling machine or the like, substantially as shown and described.
